UNITED STATES PATENT OFFICE.

JAVIER RESINES, OF MADRID, SPAIN.

CENTRIFUGAL PROCESS OF SEPARATION.

1,097,561.

Specification of Letters Patent.

Patented May 19, 1914.

Application filed May 10, 1911. Serial No. 526,267.

To all whom it may concern:

Be it known that I, JAVIER RESINES, a subject of the King of Spain, resident of Madrid, Spain, have invented a new and useful Improvement in Centrifugal Process of Separation, of which the following is a specification.

The object of my invention is to provide a centrifugal process for separating solids held in suspension in liquids, cleaning the latter by causing the liquid to follow a lengthened course proportionate to the size of the apparatus employed.

To attain this object my invention consists of an improved centrifugal process wherein the course of the liquid is alternately deflected and sinuously directed, while the liquid is subjected to the action of the centrifugal force, thus obtaining a lengthened course and consequently an increase of the time of said centrifugal action, as well as an augmentation of the radius of the overflow that produces the corresponding considerable increase of the actual acting centrifugal force.

It further consists of such process in which counter-currents against the separating force are created which aid in separating the solids from the liquids.

It further consists of such process in which the course of the liquid is alternately deflected to create counter-currents against the separating force, whereupon the liquid is finally filtered by means of and in the natural direction of the centrifugal force.

It further consists of such process and apparatus in which the course of the liquid is deflected to create counter-currents against the separating force, whereupon the liquid is passed through a filter utilizing the difference in the levels of the liquid in the chambers, thus making the liquid overflow toward the center of rotation, while the solids are thrown by the centrifugal force in an opposite direction toward the side wall.

It further consists of such process in which the body of liquid to be separated is contained in a rotating container and in maintaining the inner side of the liquid accessible to the surrounding atmosphere.

It further consists of other novel features of operation, all as will be hereinafter fully set forth.

For the purpose of illustrating my invention, I have shown in the accompanying

drawings forms thereof which may be employed by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a diagrammatic sectional view of a centrifugal separator embodying my invention. Fig. 2 represents a similar view of a centrifugal separator disclosing another embodiment of my invention. Fig. 3 represents a similar view of a centrifugal separator disclosing still another embodiment of my invention. Fig. 4 represents a similar view of a centrifugal separator disclosing still another embodiment of my invention.

Similar numerals of reference indicate corresponding parts in the figures.

Referring to the drawings, the numeral 1 indicates the cylinder or body of a centrifugal separator, suitably mounted to be revolved around its vertical axis and having an annular top 5. This cylinder is surrounded by a suitable jacket, 2, having an outlet, 3, at its bottom for the purified liquid. A feed-pipe, 7, extends to near the bottom of the cylinder, where it has an opening, 8, and serves to convey the liquid to be separated into the cylinder. Annular baffle-plates, 9 and 10, are supported in the cylinder, the plate 9 being secured to the wall of the same and the plates 10 being supported to leave an annular space between their outer edges and the wall of the cylinder and being arranged to alternate with the plate 9.

A cylindrical filtering wall, 11, is supported between the inner edge of the uppermost plate 10 and the top, 5, of the cylinder, and may be formed from any suitable or desired material permeable to liquid, such as fine wire-gauze, felt, or other straining or filtering material.

In the device illustrated in Fig. 2, the upper portion, 13, of the wall of the cylinder 105 forms the filter, being formed from any material permeable to liquid and capable of retaining the solids to be separated.

In the device illustrated in Fig. 3, the staggered baffle-plates are dispensed with, 110 there being only one annular plate, 14, which divides the cylinder in a lower portion.

partment having an impermeable wall and an upper compartment having the permeable wall 11.

In the device illustrated in Fig. 4, the 5 cylinder has no annular plates and its entire wall is permeable.

In the devices illustrated in Figs. 2, 3 and 4, an annular trough, 4, is provided near the top of the jacket and below the annular 10 top of the cylinder, and an outlet, 6, is provided from said trough.

When the cylinder is rapidly revolved and whatever liquid to be purified is fed into it through the feed pipe, the centrifugal force 15 will throw the liquid against the wall of the cylinder and the heavier solids will strike the wall and be deposited there, while the purified liquid will ascend and flow out through the filter and overflow the top of 20 the cylinder, being received in the jacket of the separator from which it flows out through the outlet at the bottom. As the liquid ascends, the baffle-plates will force it to take a sinuous or tortuous flow, whereby 25 the current, as it passes to and around the inner edge of the annular plate upon the wall, will be forced against the centrifugal force, as indicated by the arrows in Fig. 1. By creating there counter-currents, the solid 30 particles suspended in the liquid will be retarded and deposited, while the liquid ascends and flows out through the filter, where the last solids will be caught.

It will thus be seen that the course of the 35 liquid through the separator will be long compared with the height of the cylinder of the same and will be in the form of an annular or hollow cylindrical body on account of the action of the centrifugal force, and 40 that the long, deflected and tortuous course of the liquid will expose the solids held in suspension in the liquid to the centrifugal force for longer time than when the flow of the liquid is straight and unimpeded. It 45 will also be understood that by feeding the liquid at the bottom of the separator and directing it upward in its tortuous course, the force of gravity exerts a retarding influence upon the liquid, thus exposing the latter to the action of centrifugal force for a 50 comparatively long space of time and also causing the solids to precipitate by gravity. The flow of the liquid is opposed by the natural forces,—gravity and centrifugal 55 force,—whereby thorough separation is attained. This impeding of the course of the liquid and of the solids therein suspended, provides a more perfect separation and purification than is possible where the liquid is 60 thrown directly against the wall of a separator. When the feed of the liquid is so rapid in the forms of the device illustrated in Figs. 2, 3 and 4, that the filter cannot admit of the 65 discharge of all of the liquid, the latter will be

caught in the trough. If the overflowing liquid is pure, it may be drawn off at the outlet into the liquid drawn off from the bottom of the jacket, and if the overflow liquid is not pure, owing to its not being filtered, 70 it may be poured back into the cylinder through the feed-pipe or otherwise. By providing the filter wall at the inner side of the top-chamber of the cylinder, the liquid will flow against the separating force and 75 the solids still in suspension will be arrested and thrown out against the impermeable wall of the cylinder.

In the form of separator illustrated in Fig. 3, the retardation of the liquid is less 80 than in the form illustrated in Figs. 1 and 2, owing to this form only having one baffle-plate, and in the form illustrated in Fig. 4, no retardation of the liquid takes place, but the three latter forms have the annular 85 trough or gutter for the overflow liquid.

As the liquid having the solids in suspension ascends in the cylinder, each solid particle will not only travel upward until it is forced against the wall of the cylinder, but 90 will also travel around with the liquid and the rotating cylinder and baffle-plates. The molecules of the clear liquid will also travel around and upward, but, being lighter and easier movable than the solid molecules, the 95 liquid will pass quicker upward around the baffle-plates than the solids which will gradually work outward and settle upon the walls of the cylinder. The solid molecules will thus describe a helicoidal ascent until 100 they reach the wall of the cylinder and settle there, thus traveling a comparatively long distance through the separator to admit of the centrifugal force acting upon all of the solid particles in the liquid to be 105 separated and accomplishing a thorough cleaning or separation. As the baffle-plates direct the flow of the molecules alternately with and against the centrifugal force, the molecules will describe helicoidal lines of 110 alternately increasing and decreasing radii, thus exposing the heavier solid molecules to the action of the centrifugal force for a comparative long space of time.

Having thus described my invention, what 115 I claim as new and desire to secure by Letters Patent, is:—

1. The process of separating by centrifugal force solids suspended in a liquid, which consists in creating a flow of the liquid to be separated in a rotating container and directing such flow alternately with and against the direction of the separating force and maintaining the inner side of such flow accessible to the surrounding atmosphere. 120

2. The process of separating by centrifugal force solids suspended in a liquid, which consists in creating a flow of the liquid into the rotating vessel of a centrifugal apparatus, such flow being forced to travel dur- 125 130

ing a certain period of time in the same direction as the centrifugal action, and against that direction in the subsequent period of time, maintaining the inner zone of rotation 5 accessible to the surrounding atmosphere, the travel of the liquid being retarded in order to prolong the action of the centrifugal force during a considerable space of time and thus causing a greater efficiency in 10 the centrifugal separation.

3. The process of separating by centrifugal force solids suspended in a liquid, which consists in feeding the liquid to be separated

into a rotating container and directing the molecules of said liquid to travel in helical courses of alternately increasing and decreasing radii, whereby such molecules are subjected to the action of the centrifugal force for a comparatively long space of time, and maintaining the inner side of 15 such liquid accessible to the surrounding atmosphere. 20
